UNITED STATES PATENT OFFICE.

FRANK F. WEAR, OF SAN FRANCISCO, CALIFORNIA.

DESIGN FOR A COFFEE-BIN.

No. 40,085.

Specification for Design.

Patented June 22, 1909.

Application filed March 29, 1909. Serial No. 486,628. Term of patent 7 years.

To all whom it may concern:

Be it known that I, FRANK F. WEAR, a citizen of the United States, residing at San Francisco, in the county of San Francisco and State of California, have invented a new, original, and ornamental Design for Coffee-Bins, of which the following is a specification, reference being had to the accompanying drawing, forming part thereof.

The figure is a perspective view of a coffee bin, showing my new design.

I claim:

The ornamental design for a coffee bin as shown.

FRANK F. WEAR.
